(57) **CLAIM**

The ornamental design for a cornhole bag carrier, as shown and described.

DESCRIPTION

FIG. 1 is a top plan view showing the new, original, and ornamental design of a cornhole bag carrier;

FIG. 2 is a bottom plan view thereof;

FIG. 3 is a right elevation view thereof;

FIG. 4 is a left elevation view thereof;

FIG. 5 is a front elevation view thereof; and,

FIG. 6 is a rear elevation view thereof.

The broken lines shown in the drawings representing a side pocket and bottle holder form no part of the claimed design.
